UNITED STATES PATENT OFFICE.

ALVAH SWEETLAND, OF SYRACUSE, NEW YORK.

CURTAIN-FIXTURE.

SPECIFICATION forming part of Letters Patent No. 296,712, dated April 8, 1884.

Application filed September 25, 1883. (No model.)

To all whom it may concern:

Be it known that I, ALVAH SWEETLAND, of the city of Syracuse, in the county of Onondaga and State of New York, have invented 5 certain new and useful Improvements in Curtain-Fixtures, of which the following is a specification, reference being had to the accompanying drawings, in which—

Figure 1 is a perspective of the curtain 10 mounted. Fig. 2 shows plan views of the head-bracket; Fig. 3, like views of the tail-bracket; Fig. 4, like views of the spindle; Fig. 5, a cross-section of the roller on the line L; Fig. 6, a section of the roller tail-piece.

15 My invention relates to that class of curtain-fixtures known as "spring-rollers," and has reference to the means for stopping the rotation of the roller at desired points, to the brackets for supporting the roller, and to the 20 devices for connecting the roller to or mounting it upon the brackets.

It consists in the several features hereinafter described, and specifically set forth in the claims.

25 Like letters refer to like parts in all the figures.

A represents a curtain-roller of that class which is provided with an internal spiral spring secured at one end to the roller and 30 at the other to the spindle B, which is loosely connected to the roller, and prevented from rotating by the bracket C. The collar D maintains the spindle and the roller relatively concentric. The roller and spring, being of the usual construction, require no further description.

35 The spindle B is constructed, in this instance, with longitudinal V-shaped grooves *a* on opposite sides, extending the whole length 40 of the hub *x*, up to the shoulder *b*; or one groove may be used instead of two. On one side of the groove the hub *x* is flattened, as at *c*.

D is the head of the spindle, constructed of 45 a semi-spherical general form, (shown in the drawings,) the flat side being on a line with the longitudinal center line of the spindle. Through this head is a hole, *n*, perpendicular to the flat side. The collar E is bored, as at 50 *d*, to receive the bolts *m*. The line of one side of each of these bores is tangential to the

periphery of the hub of the spindle, and also to the circumference of the spindle-hole in the collar, and their sides are parallel, and each of these bores opens into the spindle-hole, and through them each of the bolts, at a certain point in the revolution of the roller, projects sufficiently to enter the groove *a* in the spindle, and so that the edge of this groove will bite into the side of the bolt and lock the 60 roller. A metallic cap or ferrule, *i*, of usual construction, covers the circumference of the collar E, and the ends of the bores or bolt-seats *d*, and retains the bolts *m* in the bores. These bolts fit loosely therein, so that they 65 will slide easily.

The bracket C is constructed with a base, a screw, F, cast into the base, a stem, *y*, and studs *o o*, one on each side, upon and at right angles to the stem, as shown in the drawings. 70 Each of these studs is constructed with a shoulder, *r*.

H is the tail-bracket, constructed the same as the bracket C as to the base and screw and stem, except that the stem carries two plain 75 cylindrical studs, *o' o'*, one on each side, and another, *s*, on the top.

N is the tail-piece upon the roller A, constructed with an outer central raised portion, in which is a cylindrical recess, *t*, of such size 80 as to freely receive either one of the studs *o' o* on the bracket H. The hole *n* in the head D of the spindle is of such size as to pass the head over the shoulders *r* upon the studs *o* on the bracket C, the shoulder preventing the 85 head from slipping or twisting off from the stud.

In the construction of spring-rollers, devices 90 dependent upon centrifugal motion have been employed as stops, and said motion has been governed by the rapidity of ascent or descent given to the curtain. So, in this instance, the centrifugal motion tends to throw the bolts *m* outward with the rapid revolution of the roller; and when said revolution is slowed down sufficiently one of said bolts approaches the spindle, and its lower end drops in the groove *a*, until it rests, or nearly rests, against the side of the groove opposite to the bolt entrance. 95 By the time the bolt has reached this point the 100 then upper side or edge of the groove comes in contact with and bites against the bolt,

crowding it against the walls of the bolt-hole, and the roller is locked. A reverse movement of the roller releases the bolt, and the lower face of the groove shoves it back part way, and 5 the flattened space *e* assists by wedging and lifting it back the remainder of the distance until it is clear. The brackets *CH* are set up by simply screwing the screw *F* into the casing or jamb of the window. The drawings show 10 the roller mounted upon the casings. When the roller is to be set up between the jambs of the window, then the stud *s* will fit into the recess *t* in the tail-piece *N*, the spindle-head *D* fitting upon one of the studs *o* on the bracket 15 *C*, the stems of the brackets being in line with the roller and not at right angles to it.

I can construct the tail-piece *N* with a projecting stud in place of the recess *t*, and by squaring off the spindle-head the roller can be 20 used upon any ordinary bracket. I can also drill holes through the stem of the bracket *H*, to take the place of the stud *o's*, to adapt it to be used with a tail-piece having a projecting stud.

25 I disclaim the following matter, herein shown and described, viz: In a curtain-roller, the end plate having grooves or recesses, one wall of each being radial and the other parallel thereto, and terminating in a shoulder, and with 30 two locking-pieces reciprocating in said recesses, to engage or disengage from the vertical recess of the spindle.

Having thus described my invention, what I claim, and desire to secure by Letters Patent, is—

1. The combination of a roller-spindle having a groove and an adjacent flat surface, and a bolt carried by a roller for locking the same by contact with the groove and the bite of the 40 edge of the groove upon the locking-bolt, substantially as and for the purpose set forth.

2. The combination of the spindle provided with the groove *a* and adjacent flat surface *c*, the collar *E*, and bolts *m*, substantially as shown 45 and described.

3. The combination of the spring-roller *A*,

spindle *B*, collar *E*, bolts *m*, and ferrule *i*, the spindle and collar being constructed and operating to bite the bolt with the edges of the groove, substantially as specified. 50

4. The head-bracket *C*, constructed with a base-screw, *F*, stem *y*, and studs *o*, provided with a shoulder, *r*, substantially as shown and described.

5. A roller-spindle constructed with hub *x*, 55 having therein a groove, *a*, and adjacent flat surface *c*, a shoulder *b*, and a semi-spherical head, *D*, having a hole, *n*, through it, by which the spindle is connected to the bracket and prevented from revolving, substantially as 60 shown and described.

6. The tail-bracket *H*, constructed with base-screws *F*, stem *y*, and studs *o's*, substantially as shown and described.

7. A curtain-fixture consisting of the roller 65 *A*, spindle *B*, collar *E*, bolt-seats *d*, and bolts *m*, engaging with the groove *a* and flat surface *c* of the spindle, the spindle-head *D*, bracket *C*, tail-piece *N*, and bracket *H*, constructed and operated together, substantially as and for the 70 purposes specified.

8. The spindle *B*, provided with a head, *D*, in combination with the bracket *C*, provided with the studs *o*, and shoulder *r*, substantially as and for the purposes set forth. 75

9. The perforated semi-spherical spindle-head *D*, in combination with a bracket having a stud, *o*, constructed substantially as described.

10. In a curtain-roller, the collar *E*, constructed with bolt-seats *d*, each being on a line 80 tangential to the spindle-hole therein, in combination with locking-bolts *m'm*, reciprocating in the bolt-seats, substantially as and for the purposes set forth.

In witness whereof I have hereunto set my hand this 22d day of September, 1883.

ALVAH SWEETLAND.

In presence of—

C. W. SMITH,
S. BROOKS BACON.
